UNITED STATES PATENT OFFICE.

GUSTAVE D. GLASER, OF CHICAGO, ILLINOIS, ASSIGNOR OF ONE-HALF TO
ALFRED KOHN, OF SAME PLACE.

DESIGN FOR A BOTTLE.

SPECIFICATION forming part of Design No. 34,818, dated July 23, 1901.

Application filed June 27, 1901. Serial No. 68,290. Term of patent 7 years.

To all whom it may concern:

Be it known that I, GUSTAVE D. GLASER, a citizen of the United States, residing at Chicago, in the county of Cook and State of Illinois, have invented and produced a new and useful Design for Bottles, of which the following is a specification, reference being had to the accompanying drawings, forming part of this specification.

Figure 1 is an elevation of the bottle, showing my new design. Fig. 2 is another elevation thereof. Fig. 3 is a bottom view thereof.

Like features are indicated by similar characters of reference in the views.

The drawings illustrating the design show a bottle having eight sides. The middle portion of the bottle is provided with a continuous curved face *a*, extending around the bottle three-eighths of its circumference, three of the vertical or upright faces *bbb* being broken or discontinued where the continuously curved face *a* is located.

The general contour of the bottle is wavy,

the sides of the bottle curving inwardly at 25 the middle. These sides bulge before reaching the neck of the bottle and then are contracted toward the neck of the bottle to produce a slight shoulder *c*. The sides of the bottle also bulge outwardly from the middle 30 before reaching the base, the sides bulging farther at the base than at the neck. The sides in their continuation to the bottom of the bottle are contracted slightly to cause a slight enlargement *d*. The drawings show 35 the neck of the bottle as being provided with beads *ff* and a rim *g*.

Having described my invention, what I claim as new, and desire to secure by Letters Patent, is—

The design for a bottle as herein shown and described.

In testimony whereof I hereunto subscribe my name this 14th day of June, 1901.

GUSTAVE D. GLASER.
